UNITED STATES PATENT OFFICE

100,512

DESIGN FOR A TUFTED RUG

Philip C. Waite, Oshkosh, Wis.

Application May 4, 1936, Serial No. 62,450

Term of patent 3½ years

To whom it may concern:

Be it known that I, Philip C. Waite, a citizen of the United States, residing at Oshkosh, county of Winnebago, and State of Wisconsin, have invented a new, original, and ornamental Design for a Tufted Rug, of which the following is a specification, reference being had to the accompanying drawing, forming part thereof.

The figure is a plan view of a tufted rug showing my new design.

I claim:

The ornamental design for a tufted rug, substantially as shown.

PHILIP C. WAITE.
